ARCHERY BOW

Meade McArdle, Rte. 2, Box 73A,
Horse Shoe, N.C. 28742

Filed Nov. 11, 1974, Ser. No. 522,344

Term of patent 14 years

Int. Cl. D22—01

U.S. Cl. D22—5

FIG. 1 is a perspective view of an archery bow showing my new design;

FIG. 2 is a side elevational view thereof; and

FIG. 3 is a rear elevational view thereof.

The arrow shown in broken lines in FIGS. 1 and 2 is for environmental purposes to aid in understanding how the bow is used.

I claim:

The ornamental design for an archery bow, substantially as shown and described.
